(57) **CLAIM**

The ornamental design for a melting plate with engraved rose petal pattern, as shown and described.

DESCRIPTION

FIG. 1 is an isometric view of the top of a melting plate having an engraved rose petal pattern according to the present invention;

FIG. 2 is an isometric view of the bottom thereof;

FIG. 3 is an elevational view of the top thereof;

FIG. 4 is an elevational view of the bottom thereof; and,

FIG. 5 is an isometric view illustrating in phantom a candle holder in which the melting plate may be disposed.

FIG. 5 is provided for context only and forms no part of the claimed design. Also, structures shown in phantom form no part of the claimed design.
